United States Patent Office.

HENRY JEFFREY, OF ST. CHARLES, MISSOURI.

Letters Patent No. 67,552, dated August 6, 1867.

IMPROVEMENT IN NAIL-EXTRACTERS.

The Schedule referred to in these Letters Patent and making part of the same.

TO ALL WHOM IT MAY CONCERN:

Be it known that I, HENRY JEFFREY, of St. Charles, in the county of St. Charles, and State of Missouri, have invented a new and improved Claw-Bar for Drawing Railroad Spikes; and I do hereby declare that the following is a full, clear, and exact description thereof, which will enable others skilled in the art to make and use the same, reference being had to the accompanying drawings, forming part of this specification, in which—

Figure 1 is a side view of my improved railroad claw-bar.

Figure 2, an edge view of the same.

Figure 3, a cross-section taken in the line $z z$, fig. 1.

Figure 4, a view of the connecting-bolt of the claw-plates.

Figure 5, a view of the claw-bar, showing its mode of application for drawing spikes.

Similar letters of reference indicate like parts.

This invention relates to a new and useful improvement in the construction of a claw-bar for drawing railroad spikes; and consists in attaching two oval-shaped steel claw-plates on opposite sides of the bent end of an iron bar or bent lever by means of a steel bolt and nut, as hereinafter more particularly described.

A represents a long iron bar or lever, bent at one end at an angle of forty-five degrees, on which bent end a , are bolted on opposite sides two oval-shaped steel plates $b b$, with a square bolt, c , to hold them rigidly in place on the bar. The plates are fastened with their major diameters at right angles to the bent end a , and therefore diagonally to the line of the bar A, as shown in fig. 1, for the purpose of changing the position and power of the fulcrum in drawing spikes by reversing the ends of the claw-plates after starting the spikes with the claw at one end. The plates $b b$ are just wide enough apart at their ends to receive the shank of a rail spike freely, and the ends have recesses cut in them to form two hooks or claws $e e$ on each end of each plate, as seen in fig. 1. The claws $e e$ are made double or single, as desired, by cutting recesses on one or both sides of the points, as shown in fig. 3. The single claws, formed by cutting recesses on the inner sides of the points, and bevelling the outer sides, as shown clearly in fig. 3, are especially adapted to the drawing of rail-chair spike, while those which have the recesses on both sides of the claws are for general use. The advantage of making the claws $e e$ double in this manner consists in doubling the capacity for service of the claw-bar by reversing the plates $b b$ when the points of the claws break, which sometimes happens when it would be inconvenient to stop work for repairs.

The manner of applying my improved claw-bar for drawing railroad spikes is illustrated in fig. 5. A long spike can be started with the claw-plates applied at one end with a short purchase, and may then be drawn, by changing ends, with a long purchase, the position and power of the fulcrum being changed by the reversal of the plates, so that the longest spike can be easily drawn without bending it.

Having described my invention, I claim as new and desire to secure by Letters Patent—

The steel plates $b b$, provided with double or single claws $e e$, in combination with the bent lever A, constructed and operating as described.

HENRY JEFFREY.
